Primary Examiner — Jonathan J Han(74) *Attorney, Agent, or Firm* — Fross Zelnick Lehrman & Zissu, P.C.; Lawrence E. Apolzon, Esq.(57) **CLAIM**

The ornamental design for a sole for footwear, as shown and described.

DESCRIPTION

FIG. 1 is a front perspective view of a sole footwear showing my new design;

FIG. 2 is an enlarged front view thereof;

FIG. 3 is an enlarged back view thereof;

FIG. 4 is a left side view thereof;

FIG. 5 is a right side view thereof;

FIG. 6 is a top view thereof; and,

FIG. 7 is a bottom view thereof.

The broken lines in the drawings show environmental subject matter that forms no part of the claimed design.

The shading in the drawings reflect levels of shading contrast. Colors form no part of the claimed design.

1 Claim, 5 Drawing Sheets(56)
